P. J. DARLINGTON

MICROMETER CALIPER

Filed May 5, 1922

Inventor
Philip J. Darlington

UNITED STATES PATENT OFFICE.

PHILIP J. DARLINGTON, OF BOSTON, MASSACHUSETTS.

MICROMETER CALIPER.

Application filed May 5, 1922. Serial No. 558,824.

To all whom it may concern:

Be it known that I, PHILIP J. DARLINGTON, a citizen of the United States, residing at 60 West Cedar Street, in the city of Boston, county of Suffolk, and State of Massachusetts, have invented a new and useful Micrometer Caliper, of which the following is a specification.

The micrometer-caliper herein described has some features and some uses in common with the micrometer-caliper of my application No. 535010 filed February 8, 1922, and my application #558,516, filed May 4, 1922.

My invention relates to improvements in micrometer-calipers designed for use in producing and for inspecting a dimension of an object, and especially for taking successive measurements of diameter during reduction of the diameter of an object toward a desired diameter and to within specified limits or tolerances above and below it.

The objects of my improvements are, first, to provide a micrometer-caliper which is rapid, accurate, and reliable in use and but little dependent upon the intelligence or skill of the user; and, second, to provide a micrometer-caliper which can be cheaply and quickly adapted to many uses and which is cheap to make and durable in use.

The nature of my invention will be best understood by reference to the accompanying drawings, in which I have shown the preferred embodiment thereof and which will now be described, it being premised, however, that various changes can be made in the construction and arrangement of the various parts without departing from the spirit and scope of the invention as defined in the appended claims.

Figure 1 is an elevation view, partly in section on the centerline of the frame and partly in section on the dotted line 1-1, Fig. 2; Figure 2, a rear elevation view without the spindle and plunger; and Fig. 3, an elevation view of the frame and index dial.

Similar numerals refer to similar parts throughout the several views.

The frame 1 slidably supports the measuring plunger 2, which is normally held in the raised or open position by the arm 3, pivoted on the stationary pin 4, the angular position of which arm is determined by the angular position of the lever 5, which is also pivoted on the pin 4. The spring

6 coiled about the pivot yieldingly presses the arm 3 against the heel 7 of the lever 5. The arm 3 and lever 5 thus form a bell-crank which is rigid in the direction of movement of the lever 5 which tends to raise the plunger 2, but which in the opposite direction yields to a pressure sufficient to overcome the tension of the spring 6. The operating lever 5 is normally held against the stop pin 36 by the spring 8. The push pin 9 detachably fastened to the free end of the lever 5 extends through the hole 10 in the frame 1 and serves when pushed in, by contact with the object being measured, or by manual operation, to displace the lever 5 against the spring 8 and let the free end of the arm 3 swing down.

The plunger 2 is tubular and has an internal thread. Threaded through the plunger and adjustable longitudinally with relation thereto is a contact spindle 11. The spindle is held in adjusted relation to the plunger by the friction of the inwardly bent segments 12 formed by splitting the upper end of the plunger 2. The arm 3 engages the plunger 2 in a slot 13 with a small end clearance 14, which permits a limited rotation of the plunger 2 in the frame 1.

The position of the plunger 2, relatively to the frame 1, is shown by the movable indicating member 15, which is connected to the plunger 2 through a multiplying device, preferably comprising the first and second pivoted arms 16 and 17 respectively, normally contacting with a knife edge 18 on the arm 3.

The member 15 preferably has a counterbalance 19 and a spring 20 in tension to draw the member 15 in the opening direction of the micrometer-caliper from the object to be measured. A toothless or friction ratchet, preferably comprising the ball 21, wedging between the inclined block 22 and the member 15, is arranged to allow movement of the lever 15 in the direction corresponding to the downward or closing movement of the plunger 2, but to normally lock the member 15 in its effort to follow an upward or opening movement of the plunger 2. The forked and counterbalanced release lever 23 is normally held by the spring 24 against the ball 21 to force it into the locking position. The handle 25, carried by lever 23, projects through the arc-shaped window 26 in position to allow the member

15 to be released by lifting the ball 21 by means of the forked lever 23.

The indicating member 15 carries a removable index plate 27 which is preferably marked with index lines 28, 29 and 30, representing, respectively, the desired size and the smallest and largest tolerated sizes of the object being measured. The symbol 31, marked on the index plate 27, represents that combination of tolerances and may agree with a corresponding mark on a simplified drawing of the object being measured. The lines 28, 29 and 30, on the index plate 27, read upon the graduated scale 32 on the beveled edge 33 of the window 34 in the frame 1. The graduations of the scale 32 are serially numbered in both directions from a zero line 35.

The operation of the device is as follows:

The micrometer-caliper is placed upon a standard gage or object of the desired size and the spindle 11 is adjusted until the mark 28 reads on the zero line 35.

The micrometer-caliper is then placed upon the object to be measured and the push-pin 9 is forced inward. This through the jointed bell-crank causes the spindle carried by the plunger to yieldingly press against the object. The caliper is then manipulated, relatively to the object, until the plunger 2 has been squared with, or has surely passed through a plane at right angles to, the object. The movements of the plunger are transmitted to the indicating member by the intermediate arms, the leverage of which is such that slight movements of the plunger are greatly increased in the indicating member. The ball 21 locks the indicating member 15 in the position of the smallest reading and the index member 15 remains in that position until manually released by means of the handle 25.

I claim:

1. In a micrometer-caliper the combination of a frame, an adjustable measuring member movably supported by the frame, means mounted on the frame and actuated from the measuring member, said means being yielding to permit the adjustment of said measuring member onto the object to be measured, an indicating member, mechanism for transmitting and multiplying the movements of said yielding means to the indicating member, and locking means for retaining said indicating member in the position of lowest measurement.

2. In a micrometer-caliper the combination of a frame, an adjustable measuring member movably supported by the frame, an angle lever pivoted on the frame and actuated from the measuring member, said lever being formed of two sections hinged together at the fulcrum of the lever, yield-

ing means engaging said sections and movably holding them in definite relation but permitting one section to be moved in one direction independently of the other section in order to permit the adjustment of said measuring member onto the object to be measured, an indicating member, mechanism for transmitting and multiplying the movements of said angle lever to the indicating member, locking means for retaining said indicating member in the position of lowest measurement, and means for releasing said locking means.

3. In a micrometer-caliper the combination of a frame, a measuring member movably mounted on the frame, a contact member arranged to receive movement from the object to be measured, a yielding connection between the contact member and measuring means, an indicating member, and means multiplying the movements of the indicating member controlled by the position of said yielding connection.

4. In a micrometer-caliper the combination of a frame, a measuring member movably supported by the frame, an indicating member movably mounted on the frame, means for actuating the indicating member from said measuring member, said means multiplying the movements of the indicating member, and a friction ratchet engaging said indicating member to permit its movement in one direction only.

5. In a measuring device a frame, a measuring means movably supported by the frame, an indicating means movably mounted on the frame, means for locking said indicating means against movement in one direction, and a plurality of levers arranged intermediate the measuring means and the indicating means for transmitting and multiplying the movement of the former to the latter means.

6. In a micrometer-caliper the combination of a frame, a plunger slidably mounted in said frame, a measuring member threaded into said plunger, an oscillating indicating member pivoted to the frame and adapted to co-operate with the measuring member, means in frictional engagement with said indicating member, said means permitting the indicating member to swing freely in one direction and locking it against swinging in the opposite direction whereby the indicating member will be detained in the position to which it is swung when coacting with the measuring member, and a plurality of co-operating levers for transmitting and multiplying the movements of the plunger to the indicating member.

7. In a micrometer-caliper the combination of a frame, a tubular plunger slidably mounted in the frame, a spindle threaded through the plunger, an indicating member pivoted to the frame and adapted to co-

- operate with the plunger, means in frictional engagement with the indicating member, said means permitting the indicating member to swing freely in one direction and 45
 5 locking it against swinging in the opposite direction whereby the indicating member will be detained in the position to which it is swung when coacting with the plunger, and means for transmitting and multiplying the movements of the plunger to the indicating member.
- 6 In a micrometer-caliper the combination of a frame, a tubular plunger slidably mounted in the frame, a spindle threaded through the plunger, an indicating lever, levers for transmitting the movements of the plunger to the indicating lever, and a rotatable clutch in frictional engagement with and designed to obstruct the movements of the indicating lever in one direction. 55
 12
- 7 In a micrometer-caliper the combination of a frame, a tubular plunger slidably mounted in the frame, a spindle threaded through the plunger, a lever engaging the plunger, an indicating lever, means frictionally engaging and obstructing the movement of the indicating lever in one direction, and a plurality of levers intermediate the plunger lever and indicating lever, for multiplying the movements of the plunger lever on the indicating lever. 60
 25
8. In a micrometer-caliper the combination of a frame bearing a graduated scale, a plunger slidably mounted in the frame, a spindle threaded through the plunger, a bell-crank lever with a yielding joint at the angle pivoted to the frame and having one end engaged with the plunger and the other end provided with a push pin, a lever with an index reading with the scale on the frame, multiplying levers interposed between an arm of the bell-crank and the index lever, whereby the movements of the plunger through the bell-crank are transmitted to and multiplied in the movement of the index lever, and means for retaining the index lever against movement in one direction while permitting movement in the opposite direction. 65
 17
9. In a micrometer-caliper the combination of a frame bearing a graduated scale, a plunger slidably mounted in the frame, a spindle adjustable in the plunger, a bell-crank lever with a yielding joint at the angle pivoted to the frame and having one end engaged with the plunger and the other end provided with a push pin, a lever with an index reading with the scale on the frame, multiplying levers interposed between an arm of the bell-crank and the index lever, whereby the movements of the plunger through the bell-crank are transmitted to and multiplied in the movement of the index lever, means for temporarily retaining the index lever against movement in one direction while permitting movement in the opposite direction, and means for releasing the index lever retaining means. 75
 25
10. In a micrometer-caliper the combination of a frame bearing a graduated scale, a plunger slidably mounted in the frame, a spindle threaded through the plunger, a bell-crank lever with a yielding joint at the angle pivoted to the frame and having one end engaged with the plunger and the other end provided with a push pin, a lever with an index reading with the scale on the frame, and multiplying levers interposed between an arm of the bell-crank lever and the index lever, whereby the movements of the plunger through the bell-crank are transmitted to and multiplied in the movement of the index lever. 80
 35
11. In a micrometer-caliper the combination of a frame bearing a graduated scale, a plunger slidably mounted in the frame, a spindle threaded through the plunger, a bell-crank lever with a yielding joint at the angle pivoted to the frame and having one end engaged with the plunger and the other end provided with a push pin, a lever with an index reading with the scale on the frame, multiplying levers interposed between an arm of the bell-crank and the index lever, whereby the movements of the plunger through the bell-crank are transmitted to and multiplied in the movement of the index lever, and means for retaining the index lever against movement in one direction while permitting movement in the opposite direction. 85
 45
12. In a micrometer-caliper the combination of a frame bearing a graduated scale, a plunger slidably mounted in the frame, a spindle adjustable in the plunger, a bell-crank lever with a yielding joint at the angle pivoted to the frame and having one end engaged with the plunger and the other end provided with a push pin, a lever with an index reading with the scale on the frame, multiplying levers interposed between an arm of the bell-crank and the index lever, whereby the movements of the plunger through the bell-crank are transmitted to and multiplied in the movement of the index lever, means for temporarily retaining the index lever against movement in one direction while permitting movement in the opposite direction, and means for releasing the index lever retaining means. 90
